MOLDED SHOE SOLE

Bernard H. Capen, Andover, Mass., assignor to
Tyer Rubber Company, Andover, Mass., a corporation of Massachusetts

Application October 28, 1949, Serial No. 5,764

Term of patent 14 years

(Cl. D7—5)

To all whom it may concern:

Be it known, that I, Bernard H. Capen, a citizen of the United States, residing in Andover, county of Essex, Commonwealth of Massachusetts, have invented a new, original, and ornamental Design for Molded Shoe Sole, of which the following is a specification, reference being had to the accompanying drawings, forming a part thereof.

In the drawings, showing my new design, Fig. 1 is a bottom plan view of a molded shoe sole; Fig. 2 is a view in side elevation, and Fig. 3 is a longitudinal sectional view taken on line 3—3 of Fig. 1.

I claim:

The ornamental design for a molded shoe sole, substantially as shown.

BERNARD H. CAPEN.
